UNITED STATES PATENT OFFICE.

IRVING A. MCCORMACK, OF NEW YORK, N. Y.

LOCK.

1,343,271.

Specification of Letters Patent. Patented June 15, 1920.

Application filed January 20, 1919. Serial No. 272,105.

To all whom it may concern:

Be it known that I, IRVING A. MCCORMACK, a citizen of the United States, and a resident of New York, in the county of New York and State of New York, have invented a certain new and useful Improvement in Locks, of which the following is a full, clear, and exact specification.

This invention relates to certain improvements on the form of lock disclosed in my Patent No. 1,219,973, and has for its object primarily to provide for use in conjunction with the lock proper of said patent a type of fragile seal which is required to be broken before the lock may be operated for being opened. The seal also serves to allow a record to be kept in association therewith of the time and place of opening of the lock as well as serving to permit a record to be kept of the container upon which the lock is employed; thus, providing a device of great usefulness for tending to prevent the doors of freight cars, buildings and other structures or inclosures from being fraudulently opened when locked.

Another object of the invention is to provide a retaining element tending to prevent the shackle of the lock from being locked until the seal is applied to the lock as well as serving to require the seal to be broken before the shackle is unlocked when locked.

A further object of the invention is to provide a protecting element whereby the alarm of the lock will be protected against being tampered with when the lock is in use.

A practical embodiment of the invention is represented in the accompanying drawing forming a part of this specification in which similar characters of reference indicate corresponding parts in all the views, the said invention being more fully described hereinafter, and then pointed out in the claims at the end of the description.

In the drawing, Figure 1 is a front elevation of one form of lock showing the improvements constituting my present invention as applied thereto.

Fig. 2 is a rear elevation of the fragile seal used on the lock.

Fig. 3 is a detail view, partly in section, of the lock with one of its side plates removed, and which shows the operative mechanism of the lock.

Fig. 4 is a sectional view taken through the lock on the line IV—IV of Fig. 1.

Fig. 5 is a sectional view taken through the lock on the line V—V of Fig. 1.

Fig. 6 is an elevation of a recording slip which may be used in conjunction with the seal of the lock.

Fig. 7 is an elevation of another form of recording slip which may be used in conjunction with the seal of the lock.

Fig. 8 is a plan of the retaining element used in the lock.

Fig. 9 is an edge view of the retaining element.

Fig. 10 is a plan of the protecting element also used in the lock, and

Fig. 11 is an edge view of the protecting element.

The invention consists mainly of employing a seal 10, a retaining element 11 and a protecting element 12 in combination with a lock, as 13, having a casing, as 14, and a shackle 15 which are preferably substantially similar to the corresponding parts of the lock shown in my Patent No. 1,219,973.

The casing 14 of the lock may be formed with a front plate 16, rear plate 17 and a peripheral wall 18 provided on the edges of these plates. Through the upper part of the wall 18 at the rear edges of the plates 16 and 17 is an opening 19 leading into the interior of the casing, and through the upper part of the peripheral wall at the forward edges of the front plate and rear plate is another opening 20 leading into the interior of the casing. Movably disposed through the rear opening 19 of the casing is one end of the shackle 15 which may be substantially the shape of an inverted U, and this shackle is of a size whereby its other end may be guided inwardly and outwardly of the opening 20 of the casing. The end portion of the shackle in the rear opening 19 of the casing is somewhat enlarged, as at 22 and the lower part of this enlarged end protrudes downwardly into the casing as well as being tapered, as at 23. Projecting downwardly also into the casing from the shackle below its tapered end is a flat presser member or extension 24 of considerably less thickness than the thickness of the enlarged end of the shackle, and this extension is formed so as to extend practically the full length of the edges of the tapered part of the enlarged end. Transversely through the central part of the enlarged end 22 of the shackle is a passage or chamber 25 one end

100

105

110

of which communicates with the opening 19, while the other end of the passage terminates interiorly of the casing. Also through the central part of the enlarged end 5 of the shackle crosswise of the chamber 25 is another passage 26 which communicates with the chamber 25, and through the front plate 16 and rear plate 17 of the casing are holes 27 and 28 which are in register with 10 the passage 26. The holes 27 and 28 are somewhat smaller than the passage 26 of the shackle, while the chamber 25 and passage 26 of the shackle may be of similar diameters. In proximity to the second end of the 15 shackle 15 is a notch 29 which is in opposed relation to the enlarged end 22 of the shackle.

When the shackle 15 is closed on the casing 14 and its notched end is inserted in the 20 opening 20 of the casing the shackle may be releasably locked by operating a mechanism, as 30, which is preferably of similar construction to the operating mechanism used in the lock disclosed in my Patent No. 25 1,219,973. The mechanism 30 consists of a slide 31 with a recess 32, and this slide has a lug 33^a for removable engagement in the notch 29 of the shackle. The slide 31 is operated by a substantially V-shaped lever 33 arranged so that the free end of one of 30 its arms is in movable engagement with the edge of the tapered end 23 of the enlarged part 22 of the shackle, while the end of the second arm of the lever is movably 35 seated in the recess 32 of the slide 31, and extending from the end part of this second arm of the lever is a pin 34. The pin 34 is in the path of the shoulder 35 of a finger 36 which is held interiorly of the casing on 40 one end of a pin 39 rotatable in an opening in the front plate 16 of the casing, and on the end of the pin exteriorly of the casing is held the upper end of a substantially rectangular bar or plate 40 for being moved 45 back and forth crosswise of the casing. Also on the V-shaped lever 33 in proximity to its apex is a lug 41 which is engaged by one end of a substantially V-shaped spring 42 having its apex arranged on a pin 43 50 projecting from the rear plate of the casing through an opening 44 in the slide 31. The free end of the second arm of the spring 42 movably abuts against the underside of the peripheral wall 18 of the casing in proximity 55 to the opening 19, and protruding downwardly from the central part of the second arm of this spring is a lug 45. The spring 42 is tensioned for normally serving to swing the second arm of the lever 33 as 60 well as the slide 31 toward the front opening 20 of the casing so that the lug 33^a of the slide will be yieldingly moved crosswise of the opening 20 as well as into and out of engagement with the notch 29 of the 65 shackle 15.

In the open end of the chamber 25 of the enlarged end 22 of the shackle 15 interiorly of the casing is removably placed an alarm 46 preferably in the form of a fulminating cap or blank cartridge adapted to be exploded by a hammer, as 47. The hammer 47 is of a form similar to the hammer employed in the lock of the above named patent, and this hammer is made of a spring metal bar bent to provide a loop 48 which 70 is disposed over a pin 49 protruding interiorly of the casing from the rear plate 17 of the casing. One of the arms 50 of the hammer 47 has a lug 50^a projecting through an opening, not shown, which is provided 75 in the rear plate of the casing for holding this arm against movement and the second arm 51 of the hammer is of a length so that its free end is in movable contact with the lug 45 of the spring 42. On the second arm 80 85 51 of the spring hammer is a head 52 arranged so as to strike the cartridge 46 for exploding the cartridge when this arm is released from the lug 45 of the spring 42 by the operation of the mechanism 30, as will 90 be hereinafter more fully explained.

The seal 10 serves to allow a record to be kept of the opening of the lock by the person so authorized as well as permitting a record to be kept of the number of the car, on 95 which the lock may be used, besides tending to prevent an attempt to fraudulently open the lock. The seal 10 is preferably in the form of a plate of porcelain, or other fragile material corresponding in shape to approximately the upper half of the front plate 16 of the casing 14 of the lock, and in the central part of the lower edge of the seal is an angular recess 53 of a size to removably accommodate the upper end of the operating bar 40 of the mechanism 30 of the lock. In the upper left hand corner of the seal or fragile plate 10 is an elongated opening, as 54, which is in register with two registered holes 55 and 56 one in the front 100 plate and the other in the rear plate of the casing. In the upper right hand corner of the seal is a second elongated opening 57 which is in register with the holes 27 and 28 of the casing besides being in register 110 with the passage 26 of the enlarged part 22 of the shackle.

The retaining element 11 is in the form of a bolt which is freely rotatable in the holes 55 and 56 of the casing of the lock as well 115 as being rotatable in the opening 54 of the fragile seal 10, and this bolt is of a length to extend through this opening of the seal. On the end of the bolt exteriorly of the seal is an elongated flat head 59 which is similar 120 in shape to the shape of the opening 54 of the seal, but this head is slightly smaller than the opening to allow the seal to be removably guided over the head. The part of 125 the bolt between the front plate and rear 130

plate of the casing of the lock is enlarged, as at 60, in substantially a rectangular shape, as viewed in cross section, and this rectangular enlarged part is of a length approximately equal to the distance between the front plate and rear plate of the casing of the lock. The flat faces of the enlarged part 60 of the bolt coincide with the flat faces of the head 59 of the bolt, and when the head of the bolt is arranged, as shown in Fig. 1 of the drawing, crosswise of the opening 54 of the seal 10 one of the faces of the enlarged part 60 will be adjacent to or in contact with the end of the notched shackle 15 when locked to the casing. When the bolt is in this position its head 59 serves to lock the seal 10 on the casing of the lock in a manner whereby the seal must be broken across its opening 54 before being removed from the casing, and also when the bolt is in this position its enlarged part 60 serves to prevent the bolt being rotated until the shackle is unlocked by operating the bar 40 to operate the mechanism 30. When the shackle is unlocked and its notched end is swung outwardly of the casing the bolt may be turned one half a revolution, and its flat enlarged part 60 will be likewise rotated so that one of its edges will extend toward the opening 20 of the casing sufficient distance to prevent the shackle from being relocked until a new seal is applied to the casing of the lock, as will be subsequently explained.

The protecting element 12 is also in the form of a bolt which is freely rotatable in the registered openings 27 and 28 of the casing of the lock, but the bolt is held against rotation in the passage 26 of the enlarged part 22 of the shackle 15. The bolt or protecting element is of a length to extend beyond the seal 10 in the opening 57 in which the bolt is also freely rotatable. On the end of the bolt protruding through the opening 57 of the seal is a flat head 61 corresponding in shape to the rectangular opening of the seal, but this head is somewhat smaller than the opening so that the seal may be easily guided thereover. By forming this opening of the seal and the head 61 of the bolt or protecting element 12 of rectangular shapes the bolt when turned so that its head is crosswise of the opening of the seal this bolt and the retaining bolt 11 will cause the seal to be locked on the casing of the lock. The part of the protecting bolt 12 in the opening 26 of the enlarged part 22 of the shackle is, as at 62, in approximately a triangular shape and the shackle is rigidly held on this triangular part to prevent tampering with the fulminating cap or blank cartridge 46 when applied in the chamber 25 of the shackle by inserting a sharp instrument in the rear of the chamber through the opening 19 of the casing of the lock. To prevent backfire of the fulminating cap 46 when exploded ex-

tending interiorly of the casing of the lock from its front plate is a lug, as 63, which is arranged so that the head of the fulminating cap will be adjacent thereto when the shackle is closed on the casing 14.

70

In the rear face of the fragile seal 10 is a recess 64 for reception of a strip of paper or cardboard or other suitable material, as 65 Fig. 6, on which the seal member, or the number of the car, or any other record may be inscribed so that a trace of the opening of the lock may be kept. If desired one or more strips of paper or cardboard or the like, as 66 Fig. 7, having holes 67 and 68 may be guided over the bolts 11 and 12 so as to be disposed between the seal 10 and the casing of the lock for keeping desired records thereon, such as the time and place and by whom the lock was unlocked.

75

When the lock is used the notched end of the shackle 15 is released by swinging the bar 40 toward the forward edge of the casing. The shoulder 35 of the finger 36 will then engage the pin 34 of the V-shaped lever 33, and this lever will be swung toward the enlarged part 22 of the shackle. The slide 31 will also be likewise moved, and in turn the lug 33^a of the slide will be removed from the notch 29 of the slide. The shackle is then swung open from the casing of the lock, 90 and with this movement of these parts of the mechanism 30 the arm 51 of the spring 47 will also be released from the lug 45 of the spring 42. When the shackle 15 is swung sufficient distance so that the end of the 100 chamber 25 of the shackle normally on the interior of the casing 14 is out of the opening 19 of the casing the fulminating cap or blank cartridge is placed in the chamber. With the opening movement of the shackle 105 the protecting element or bolt 12 will be also turned to cause the head 61 of this bolt to be rotated from a position transversely of the casing of the lock to a vertical position, and the retaining element or bolt 11 is likewise turned. One or more of the strips 66 are also arranged on the bolts 11 and 12, after which the strip 65 is placed in the recess 64 of the seal 10, and the seal is guided over the heads of the bolts as well as being positioned 110 in straddle arrangement over the upper end of the bar 40, as shown in Fig. 1, so that the strips 65 and 66 will be between the seal and the casing of the lock. The retaining bolt 11 is then turned so that its head 59 is 115 crosswise of the opening 54 of the seal at which time the enlarged part 60 of this bolt will also be revolvably moved to allow the notched end of the shackle to be inserted in the opening 20 for being locked to the casing, as illustrated in Fig. 3. With the swinging of the shackle 15 to an open position from the casing 14, as above explained, the tapered end 23 of the enlarged part 22 of the shackle will pass above the adjacent end 120

125

130

of the arm of the V-shaped lever 33 and the flat presser member or extension 24 of the shackle will engage the arm 51 of the spring 47 for forcing this arm in a direction to cause its free end to engage the lug 45 of the spring 42. The head 52 of the spring hammer 47 will thus be arranged for being released to explode the fulminating cap or blank cartridge 46, and when the shackle is 10 swung to a closed position on the lock, also as above explained, the tapered end 23 of the enlarged part 22 of the shackle will reengage the adjacent arm of the V-shaped lever 33 which in turn will cause the slide 31 with the lug 33^a to be guided toward the rear edge of the casing 14 to allow the notched end of the shackle to be inserted sufficient distance into the casing through its opening 20. The tension of the spring 42 will cause a reverse movement of the V-shaped lever, besides causing a reverse movement of the slide 31 to reinsert the lug 33^a into the notch 29 of the shackle.

25 In order to unlock the shackle when the lock is in use, the seal 10 should be broken to permit its removal entirely from the casing, and the severed parts of the seal together with the strips 65 and 66 may be preserved 30 for keeping a record of the opening of the lock. The mechanism 30 is then operated, as hereinbefore explained, to unlock the shackle, and with the operation of the mechanism the cartridge 56 will be exploded 35 by the hammer 52 on the release of the arm 51 of the spring hammer 47 with the lug 45 of the spring 42. The explosion of the cartridge 46 will thereby sound an alarm so that the opening of the lock may be investigated to find out if the lock was tampered with by an unauthorized person.

In the foregoing description, I have em-

bodied the preferred form of my invention, but I do not wish to be understood as limiting myself thereto, as I am aware that 45 modifications may be made therein without departing from the principle, or sacrificing any of the advantages of this invention, therefore I reserve to myself the right to make such changes as fairly fall within the 50 scope thereof.

Having thus described my invention, I claim as new and desire to secure by Letters Patent:—

1. In a lock having a casing with a pivoted shackle as well as carrying an alarm adapted to be set when the shackle is closed on the casing, a protective element associated with the pivot of the shackle for preventing the alarm being tampered with from 60 the exterior of the casing when the alarm is set.

2. In a lock having a casing with a pivoted shackle provided with a chamber for removably holding an explosive element 65 adapted to be exploded interiorly of the casing when the shackle is closed on the casing, a protective element in the chamber for preventing the explosive element being tampered with from the exterior of the casing. 70

3. In a lock, a bolt element pivoting a shackle to the casing of the lock, said shackle having a chamber so that the bolt element is disposed thereacross and the part of the bolt element within the chamber being formed 75 whereby entrance to the chamber from the exterior of the casing will be obstructed when the shackle is closed on the casing.

This specification signed and witnessed this 18th day of January A. D. 1919.
